Attorney.

UNITED STATES PATENT OFFICE.

EDWIN GRAY, OF MAPLEWOOD, MISSOURI.

WEATHER-SHIELD FOR SPRING-SHADE AWNINGS.

1,390,527.

Specification of Letters Patent. Patented Sept. 13, 1921.

Application filed December 8, 1919. Serial No. 343,435.

To all whom it may concern:

Be it known that I, EDWIN GRAY, a citizen of the United States, residing in Maplewood, county of St. Louis, and State of Missouri, 5 have invented a certain new and useful Weather-Shield for Spring-Shade Awnings, of which the following is a specification.

My invention relates to a weather-shield adapted to be carried by the upper edge of a 10 spring shade awning and adapted to be so formed as to rest just above the awning when the awning is in its rolled position to protect the same from the weather thereby greatly reducing deterioration thereto due 15 to water or snow standing thereon and sun shining thereon when not in use.

A further object of my invention is to provide the awning with a weather-shield to protect the awning from the weather so 20 that the awning need not be taken down and stored away for the winter.

With the above and other objects in view, the shield consists in the novel construction described in the specification and finally 25 pointed out in the claims hereto appended.

Referring to the accompanying drawings forming a part of the specification, wherein like characters of reference denote similar parts throughout the several views:

30 Figure 1, is a view in perspective of a spring shade awning applied to a window, and provided with a weathershield constructed and carried by the awning in accordance with my invention.

35 Fig. 2, is a perspective view of the weather-shield, clearly showing the rear portion thereof and the manner of securing same to the upper edge of a spring-shade awning.

Fig. 3, is a side elevation of the weather- 40 shield as applied to the awning and shown in its lowermost position acting as a protection or weather-proof shield for the awning when in its rolled position.

Referring to the drawings, the reference 45 character 1 designates a window frame upon which a spring-shade awning roller 2 is carried adjacent the meeting rails of the window by means of the brackets 3. The awning carried thereby is divided into two sections, namely the lower awning section 4 and the upper awning section 5 having the upper looped and hemmed edge 6 adapted to carry the filler stick 7. The lower end of this type of awning is also looped and 55 hemmed as at 8 and adapted to receive the cross-pieces 9 of the supporting arms 10 car-

ried at their lower ends in the pivoted sockets 11.

In carrying out the aim of my invention I employ a suitable shaped weather-shield 60 comprising a back plate 12 which is adapted to be fixed to the upper edge of the awning section 5 by means of suitable fastening means, such as screws 13 which are adapted to enter the wood filler-strip 7 for securely 65 holding the plate 12 in position. The back-plate 12 is preferably provided with the cut-away portion 14 to permit the operating cord to be attached to the filler-strip 7.

The back-plate 12 is bent at a substantially 70 right angle to provide the top shield section 15, which top shield section gradually projects or extends downwardly and forwardly from the back-plate section 12 and finally at its forward ends terminates in the slightly 75 curved front section 16 to provide a positive water-drip as at 17.

From the foregoing description, it will be observed that I provide an efficient weather- 80 shield for the awning when in its rolled position and one which moves with the upper section 5 of the awning when shifted from one position to another.

It will be readily seen that when the awning is in its rolled position as shown in 85 Fig. 3, which is the position it assumes when not in use for shade, that the weather-shield fully covers or spans the rolled awnings from above, and positively prevents rain or snow from accumulating thereon 90 and also prevents the sun from shining directly thereon, this protecting the awning from all weather-conditions which results in protecting the awning from unnecessary exposure from above and preventing 95 unnecessary deterioration of the awning even though it remains fixed to the window-frame all year around.

As the greatest damage to the cloth of an awning is caused by water and snow 100 standing thereon which causes the cloth to rot, and weaken in streaks or spaces, it will be observed that my improved weather-shield will eliminate the exposure of the awning to these fatal conditions, when 105 rolled, and provide an effective protection therefor from rain, snow and sun-shine.

The many advantages of the herein described weather-shield due to its construction and method of application to the awning will be readily apparent to those skilled 110 in the art to which the invention relates.

While I have described the structure of device I now consider to be the best embodiment thereof, I desire to have it clearly understood that the shield shown is merely 5 illustrative and that I reserve the right to make any changes or modifications thereof as may fairly fall within the principle of my invention and within the scope of the claims hereto appended when fairly construed.

What I claim is:

1. In combination with a spring-shade awning, a weather shield comprising a plate having a portion thereof adapted to be secured to the upper edge of the awning so as to move therewith, said plate being bent to provide a forwardly extending shield adapted to protect the awning from the weather when in its rolled up position.
2. In combination with a spring-shade awning, a weather shield comprising a plate

adapted to be secured to the upper edge of the awning so as to move therewith, said plate having a forwardly extending shield portion terminating in a suitably curved forward edge to provide a positive water-drip, said shield portion adapted to cover the awning when the awning is in its rolled up position to provide an effective weather-proof shield therefor.

3. A weather-shield for awnings comprising a plate portion adapted to be secured to the awning, said plate being bent at a substantially right angle to provide a forwardly extending awning shield section, and said awning shield section terminating in a curved forward edge to provide an effective water-drip.

In testimony whereof, I have hereunto signed my name to the specification.

EDWIN GRAY.
